UNITED STATES PATENT OFFICE.

SIGMUND BERGMANN, OF NEW YORK, N. Y.

TELEPHONE.

SPECIFICATION forming part of Letters Patent No. 337,231, dated March 2, 1886.

Application filed December 4, 1883. Serial No. 113,502. (No model.)

To all whom it may concern:

Be it known that I, SIGMUND BERGMANN, of New York city, in the county and State of New York, have invented a certain new and 5 useful Improvement in Telephones, of which the following is a specification.

The object of my invention is to produce a telephone-transmitter employing metallic contact-points or electrodes controlled by the 10 movement of a diaphragm which shall efficiently transmit articulate speech.

In the joint application of Thomas A. Edison and myself, filed November 13, 1883, (Serial No. 111,644,) are set forth means for so 15 limiting the movements of the diaphragm, and hence those of the electrodes or contact-points in a telephone of the kind just mentioned, that they can never be moved apart, even by the strongest sound-vibrations, so far that they 20 will not be in contact at the beginning of the next succeeding vibration, each vibration, therefore, being responded to from the normal or closed condition of the circuit. In that application this effect is produced by the use 25 of a diaphragm having behind it a filling of oil or equivalent material, which retards its movement, to which diaphragm one electrode or contact-point is attached, while the other is held rigidly.

30 My present invention relates to a different apparatus for accomplishing the same limitation of the movement of the electrodes; and it mainly consists, first, in the employment of an elastic diaphragm carrying an electrode, in 35 connection with another diaphragm carrying the other electrode, the latter diaphragm being provided with the liquid body for limiting its movement; and, second, in placing such liquid on both sides of the diaphragm affected 40 by it, whereby the limitation of its movement is more effectively attained.

In carrying out my invention I place in a suitable case a suitable elastic diaphragm, which may be of metal or of insulating material—such as mica—and to this I attach one of the platinum or equivalent metallic electrodes. The opposing electrode is attached to another diaphragm having a diaphragm placed a short 45 distance on each side of it, and the intervening spaces are filled with oil or other suitable liquid. Instead, however, of a diaphragm ex-

tending across the entire space within the frame, the electrode may be attached to a narrow elastic strip, or to a central plate connected by springs with the casing. These devices I 55 consider equivalents of the diaphragm. The electrodes or contact-points are adjusted before working, so as to be in contact with each other. Preferably the sound-waves are projected against the single elastic diaphragm, 60 and the vibrations thereof are communicated to the contact-point attached thereto. The liquid prevents the opposing diaphragm from being pushed back too far, and the inelasticity of said diaphragm prevents the vibrating 65 contact-point from rebounding so far as to produce an excessive separation of the electrodes.

The accompanying drawing is a sectional view of a telephone embodying my invention.

A is a suitable case of insulating material 70 having a mouth-piece, B. C is an elastic metal diaphragm. D is a similar diaphragm having a diaphragm, E or E', on each side of it, and the spaces thus formed are filled with oil, F, or other suitable liquid. A contact-point, a, is 75 carried by the diaphragm C, and a contact-point, b, by the diaphragm D, the same extending through an aperture in diaphragm E to meet point a. Connections are made to the contacts through the diaphragms by wires 1 80 and 2. The sound-waves are projected upon the diaphragm C and communicated to the contact-point a, and the diaphragm D, with its surrounding liquid, prevents the too great separation of the contact-points, while the necessary movement to produce the current changes 85 is permitted.

What I claim is—

1. In a telephone, the combination of a diaphragm free to move under sound-vibrations, 90 carrying one contact-point, and a diaphragm provided with a liquid body limiting its movement, carrying the other contact-point, substantially as set forth.

2. In a telephone, the combination, with a 95 diaphragm and an electrode controlled thereby, of a liquid body on each side of said diaphragm, for limiting its movement, substantially as set forth.

3. In a telephone, the combination of three 100 diaphragms and a liquid body on each side of the central diaphragm, for limiting its move-

ment, said central diaphragm controlling an electrode, substantially as set forth.

4. In a telephone, the combination of a diaphragm free to move under sound-vibrations and carrying a contact-point, and a diaphragm carrying another contact-point and having a liquid body on each side of it, for limiting its movement, substantially as set forth.

5. In a telephone, the combination of a diaphragm free to move under sound-vibrations and carrying a contact-point, and a diaphragm

carrying another contact-point and having a diaphragm on each side of it, the spaces between the three last-mentioned diaphragms being filled with liquid, substantially as set forth.

This specification signed and witnessed this 1st day of December, 1883.

SIGMUND BERGMANN.
